UNITED STATES PATENT OFFICE.

CHARLES A. BABCOCK, OF BUFFALO, NEW YORK, ASSIGNOR TO PRATT & LETCHWORTH, OF SAME PLACE.

DESIGN FOR A CARRIAGE-STEP.

SPECIFICATION forming part of Design No. 15,761, dated February 3, 1885.

Application filed December 31, 1884. Term of patent 7 years.

To all whom it may concern:

Be it known that I, CHARLES A. BABCOCK, a citizen of the United States, residing at Buffalo, in the county of Erie and State of New York, have invented and produced a new and original Design for Carriage-Steps, of which the following is a specification.

This design relates to the ornamentation of the upper surface of a carriage-step by means of ornamental ribs; and it consists of the special features which will be hereinafter described and claimed, and which are represented in the accompanying drawings, consisting of two sheets, in which—

15 Figure 1 represents a plan view of a carriage-step embodying my new design. Fig. 2 is a similar view showing a slightly modified form of my design.

Like letters of reference refer to like parts 20 in both figures.

A represents the plate of the carriage-step, made square or rectangular in form, and provided with a marginal rib, a.

B represents an annular row of circular ornaments between two concentric circular ribs 25 or rings, b b'.

C represents four groups of parallel ribs upon the corner portions of the plate outside

of the outer ring, b'. The ribs in each group are parallel with the rib extending diagonally 30 from the corner of the plate to the ring b'.

D represents a central ornament within the inner ring, b.

In the design represented in Fig. 1 the central ornament, D, is composed of a series of 35 pointed ornaments grouped radially around a common center.

In the modified design represented in Fig. 2 the central ornament, D, consists of lozenge-shaped ornaments, each having two blunt or 40 concave corners.

e are openings formed in the plate in the circular ornaments B.

I claim—

The design for a carriage-step, consisting of 45 a central ornament, D, an annular row, B, of circular ornaments surrounding the same, and groups of ribs, C, on the plate outside of said annular row of ornaments, substantially as shown and described.

Witness my hand this 19th day of November, 1884.

CHAS. A. BABCOCK.
